GUY A. VOORHEES, OF INDIANAPOLIS, INDIANA

HOT-AIR-FURNACE HEAT-CONTROL SYSTEM

Application filed February 28, 1929. Serial No. 343,485.

This invention relates to means comprised in the system of controlling heat in dwellings or other buildings heated by means of hot-air furnaces, the invention having reference 5 more particularly to means for controlling air circulation either by gravity as commonly, or by the forced circulation system, or by both combined.

An object of the invention is to provide a 10 simplified and improved hot-air furnace heat control system, and apparatus thereof which shall be of such construction as to be adapted to be manufactured at moderate cost and readily installed, and which shall be highly 15 efficient in operation.

Another object is to provide an improved 20 control unit adapted to be incorporated with an air-circulation duct and to control circulation of air in accordance with heating requirements, and without necessitating but 25 permitting elaborate automatic control devices.

Another object is to provide an improved 30 control unit which shall be of such construction as to be simple and reliable without likelihood of accidental derangement and impairment of functions in operation, which might under adverse conditions result from long use.

A further object is to provide an improved 35 control unit structure which may comprise various standard parts or elements that may be readily obtained from various manufacturers or dealers supplying reliable articles, in order that a dependable heat control system may be provided at low cost which shall be economical and durable in use.

With the above-mentioned and other objects in view, the invention consists in a 40 unitary control apparatus having novel construction and arrangement of elements including a shutter, an electric fan or blower and means adapted to control the shutter and the fan; and further, the invention consists in the parts and in the combinations and arrangements of parts as hereinafter 45 particularly described and definitely claimed.

Referring to the accompanying drawings, Figure 1 is a fragmentary vertical section 50 of a building in which a hot-air furnace is

installed and provided with the invention; Fig. 2 is a section on the line II—II in Fig. 1 on an enlarged scale; Fig. 3 is a section approximately on the plane of the line III—III in Fig. 2, showing two shutters as a 55 preferable construction and in closed position; Fig. 4 is a section approximately on the line IV—IV on Fig. 2; Fig. 5 is a section similar to Fig. 3, but with the shutters in open position; Fig. 6 is a section corresponding mainly to the plane of the line II—II in Fig. 1 but having modified internal structure; Fig. 7 is a section corresponding approximately to the plane of the line VII—VII in Fig. 6; and Fig. 8 is a side elevation 60 of control devices appearing mainly in Figs. 1 and 2, but on an enlarged scale.

Similar reference characters in the different figures of the drawings indicate corresponding elements or features of construction herein referred to in detail.

As an aid to an understanding of the invention and its mode of application, a portion of a dwelling is illustrated, the numeral 1 indicating the floor of the basement or 75 cellar of a building, 2 a wall thereof, 3 the floor above the basement and 4 a wall portion of a room above the main or ground floor, the numeral 5 designating a conventional or any suitable hot-air furnace having a draft pipe 6 and a hinged gravity-closed draft regulator or damper 7 commonly controlled by means of a chain 8 extending up and into a room or compartment and adapted to be suitably connected to an 80 anchorage device 9 on the wall of the room, the chain extending through the floor 3 and being suitably guided over a guide sheave 10 and under a similar sheave 11 suitably supported under the floor.

Commonly a cold-air duct is connected with the air space that is provided between the main furnace structure and its casing, in some situations beneath the floor line but preferably above the floor line as shown, a suitable adapter 12 being provided which is suitably attached to the furnace casing and having a flange 22 on its inlet end whereby to secure a duct section thereto which in the present invention is termed a control box 100

to which a main cold-air duct section 14 is connected that extends from the floor 3 and has an inlet upper end anchored in the floor and preferably provided with a grating 15, the lower end of the duct being located on the floor 1 and provided with a flange 16. Conventionally the casing of the furnace has a suitable number of discharge pipes 17 connected therewith to supply the various compartments of the building with heated air by an arrangement of the pipes in a conventional manner.

The control box as preferably constructed is of sheet metal and particularly comprises a bottom plate 18, opposite side wall plates 19 and 20 and a top plate 21, the wall plates and the top plate having each a flange 22 on one end and a flange 23 on the opposite end thereof for securing the box to the flanges 13 and 16. In the preferred form of structure, as may be preferred in the larger sizes a vertical partition plate 24 is arranged intermediately of the side walls and fixed to the bottom and top plates, and a horizontal dividing plate 25 is arranged intermediately of the bottom and top plates and fixed to the side plate 20 and the partition plate 24. A suitable number of hinges 26, 26' are connected to the top of the bottom plate 18 and a shutter 27 is connected to the hinges so as to be inclined when in closed position and contacting with the dividing plate 25. A number of hinges 28, 28' are connected to the top of the plate 25 and support a shutter 29 in inclined position when closed against the top plate 21, so that the shutters when released shall swing downward by force of gravity to open position. A control chain 30 is connected to the upper shutter 29, the lower shutter having a chain 30' connected thereto and to the upper shutter preferably by connection with the chain 30 which extends upward through an opening 31 in the top plate 21 and in contact with the guide sheave 32 mounted on a suitable bracket 33 secured upon the top plate. The bracket preferably is provided with a substantial base 34 to directly support it upon the top plate. A post 35 preferably is provided and suitably supported upon the top plate, preferably being fixed on the base 34 and supports a guide sheave 36 for the chain 30. A switch lever 37 is pivoted at one end to the bracket, and a chain 38 is connected to the opposite end of the lever and preferably to the chain 8 and also to the chain 30, it being designed that the lever swing downward by force of gravity to open an electric switch which may be variously constructed, and to overcome possible frictional resistance a coil spring 39 preferably is connected to the lever 37 and to the base 34 so as to pull the lever downward when not purposely held up by its control chain.

The space on one side of the partition 24 in which the shutters are arranged as described constitutes a duct for gravity circulation, the space on the opposite side of the partition providing a duct for forced circulation and is partially closed by a front plate 40 fixed to the partition plate and the opposite side plate 19 and also to the bottom plate and the top plate of the box, and it has a central circular aperture and preferably a collar 41 at the edge of the aperture. An electric fan motor 42 is arranged in the control box, and is adapted to operate a rotary fan 43, being suitably mounted upon a stand 44 that is secured upon the bottom plate 18 so as to permit the fan blades to operate in the collar 41 and force cool air therethrough towards the furnace.

In a slightly modified form of structure 85 a single shutter 45 is connected to the hinges 26, 26' and extends upward at an inclination to the top plate 21 and from one to the opposite one of the side plates and has a central collar 46 thereon arranged on the edge of an aperture 47 in which the fan blades may operate, the upper portion of the collar being broader than the lower portion thereof agreeably to the degree of inclination of the shutter, the shutter being drawn up to closed position and controlled by means of the chain 30 by which the shutter may be allowed to swing downward to permit gravity circulation, forced circulation being accomplished through the shutter when it is in 100 closed position.

The preferred form of electric switch is that commonly designated as a mercury switch comprising a container 48 mounted on the switch lever 37 and containing a suitable quantity of mercury which may be caused to flow to one end of the container that has an electric circuit wire 49 suitably connected therewith to provide a switch point on the inside of the container. The mercury is constantly in contact with a switch point on the end of a circuit wire 50 that is connected with the under portion of the container and flows away from the other point when the switch lever swings 115 downward. The circuit wires are appropriately connected with the fan motor and with a source of electric energy.

In practical use the control of the heat in the building is most advantageously accomplished by use of the single chain 8, the furnace being properly supplied with fuel. When only moderate heat is required, the chain may be lowered to close or partially close the draft regulator 7 and open the electric switch so that the fan cannot operate, while the shutters are caused to be opened to permit gravity circulation of the air. When more heat is required in the building the chain is drawn upward and fastened, 130

causing the regulator 7 to be opened while the shutters in the control box are drawn up to closed position and the electric switch automatically operated so as to close the circuit and result in operation of the fan which forces the air from the cold-air duct to the furnace and thence through the distributing pipes to the various rooms, inevitably inducing rapid flow of the cooler air from the rooms and down the cold-air duct to the fan, with the result that the circulating air is rapidly heated and forced onward while impure air is drawn from the heated rooms.

What is claimed is:

1. A hot air furnace heat control system including a heating furnace, a cold-air duct, a control box to conduct air supply from the duct to the furnace, the box having a hinged gravity-opened regulating shutter, a gravity-opened electric switch in circuit mounted upon the control box, an electric fan motor mounted in the control box with controlling circuit connection with the switch, and co-operating means comprising a chain to pull and close the switch and a chain to pull and hold the shutter to closed position.

2. A hot air furnace heat control system including a heating furnace, a cold-air duct connected with the furnace and having a control box forming a section thereof provided with a bottom having hinge devices thereon and a top having an opening therein, a shutter in the control box connected to the hinge devices and having a chain connected thereto normally holding the shutter at an inclination, the chain extending upward through said opening, and an electric fan mounted upon said bottom, the fan and the shutter occupying the area of the cross-section of the control box.

3. A hot air furnace heat control system including a heating furnace, a cold-air duct connected with the furnace and having a control box section provided with a bottom having hinges and a top having an opening therein, a shutter in the control box connected to the hinges, a guide sheave mounted upon the top of the control box adjacent to said opening, a chain connected to the shutter and extending through said opening and over said sheave to support the shutter at an inclination, and an electric fan mounted upon said bottom.

4. In a hot air furnace heat control system, the combination of a control box comprising a bottom plate and a top plate, and also side plates; a control plate arranged to extend from said bottom plate to said top plate to co-operate therewith and having a central aperture, and also a collar on the edge of the aperture; an electric motor supported upon said bottom plate and a rotary fan thereon positioned to operate in said collar; an electric circuit for the motor; a

heating furnace; and a cold-air duct connected with said box and said furnace.

5. In a hot air furnace control system, the combination of a cold-air duct provided with a control box section to regulate flow of heating air through a furnace, the control box being provided internally with a regulating shutter and an electric motor and fan and externally with a shutter controller and means to control the motor comprising a gravity-opened electric switch in circuit with the motor and having a control lever, and a device coupling the shutter controller with said lever to synchronously close the shutter and the electric switch.

6. In a hot air furnace heat control system, the combination of a cold-air duct with a furnace, a control box connected with the duct and provided with a hinged gravity-opened shutter, a chain connected to the shutter and extending through the top of the control box, an electric switch lever pivoted upon the top of the control box, an electric fan motor supported in the control box, electric make-and-break devices operatively controlled by the switch lever and having electric circuit connection with the motor, and a control chain connected to the switch lever.

7. In a hot air furnace heat control system, the combination with a heating furnace and a draft regulator thereon, and a draft control chain connected to the regulator, of a cold-air control box connected with the furnace, a shutter and an electric fan motor supported in the control box, a chain connected with the shutter and the draft control chain, an electric switch mounted upon the control box and having a switch lever, a circuit wire in connection with the switch and the motor, and a chain connected with the draft control chain and also with said switch lever.

8. In a hot air furnace heat control system, the combination of a cold-air control box comprising a bottom plate and a top plate and also opposite side plates, the box having a vertical partition and a horizontal dividing plate therein on one side of the partition and also a front plate arranged on the opposite side of the partition and having a central aperture; a shutter hinged to said bottom plate below said dividing plate, a shutter hinged to said dividing plate, a control chain connected to the shutters and extending through said top plate, and an electric fan supported upon said bottom plate adjacent to said front plate.

In testimony whereof, I affix my signature on the 21st day of February, 1929.

GUY A. VOORHEES.
